DIRECTION FINDING ANTENNA SYSTEM

Gordon S. Burroughs, Forest Hills, N. Y., assignor
to Federal Telephone and Radio Corporation,
New York, N. Y., a corporation of Delaware

Application June 25, 1945, Serial No. 601,386

14 Claims. (Cl. 343—113)

1

The present invention relates to direction finders and particularly to that type of direction finder which utilizes an elevated "H" Adcock type antenna system.

If a perfectly symmetrical antenna system of the "H" Adcock type were located in free space remote from all objects, no polarization errors would be introduced. In attempting to approximate this condition, such arrays have been arranged on wooden towers high above the ground. While this has to some extent lessened the effect of proximity to ground, it has not altogether obviated it. Furthermore the use of very high towers is, in many cases, impractical particularly for portable direction finders. When waves having horizontal components impinge on the horizontal conductive members, they induce voltages in said members. These members are capacitively coupled through many stray capacitances to the antenna units and introduce voltages into said antenna units. If the introduced voltages balance, there will be no resultant output due to the horizontal wave components. Since these stray capacitances are not symmetrical in the antenna system due to the proximity to earth and other bodies, as well as other factors, these introduced voltages tend to be unequal and to introduce error. The problem is further aggravated by local conditions which are changing and require rebalancing of the system, and even more so when the system is moved from place to place as in portable units.

In such systems another problem, which complicates that of balancing the antenna system for correction of polarization error, is that concerned with obtaining a sharp null. If when the system is positioned transversely to the direction of propagation of an incoming wave, unequal voltages are induced in the upper arms or lower arms, there would be a resultant current output from the system instead of a zero output, and consequently a poor null would be obtained.

The problems hereinabove discussed depend for their solution on adjusting the antenna system under varying local conditions so that the system including its leads is electrically substantially symmetrical.

An object of the present invention is the provision of apparatus and a method for adjusting an antenna system of the type described so as to produce substantially electrical symmetry therein.

Another object of the present invention is the provision of an apparatus and method for balancing an antenna system of the type referred to

2

so as to substantially eliminate polarization errors.

Another object of the present invention is the provision of apparatus and a method associated with a direction finder whereby such antenna systems may be readily balanced or rebalanced by relatively unskilled personnel.

Still another object of the present invention is the provision of apparatus and a method for 10 adjusting such antenna system to obtain a good null.

A further object of the present invention is the provision of a direction finder including an antenna system of the type referred to hereinabove 15 including apparatus enabling the ready adjustment of the antenna system to obtain substantial electrical symmetry thereof.

Other and further objects of the present invention will become apparent and the invention will 20 be best understood from the following description of an embodiment thereof, reference being had to the drawing, in which the figure is a schematic and block diagram of a direction finder including an antenna system of the "H" type embodying 25 my invention.

Referring now to the figure, the "H" type Adcock antenna system there illustrated, includes four antenna units 1—4 of which antenna units 1 and 2 are the upper pair and 3 and 4 are the 30 lower pair, with antenna units 1 and 3 being on the left side and antenna units 2 and 4 being on the right side as viewed in said figure. Antenna units 1—4 are cross-connected by transmission lines 5 and 6. However, in accordance with my 35 invention, transmission lines 5 and 6, which may be in the form of coaxial lines, are not directly connected to said antennas but are coupled to said antenna units through couplers for antenna units 1—4 respectively.

40 In accordance with my invention, balancing is accomplished by controlling the relative gain of the coupling units 7—10. I prefer to employ couplers which, while giving variable gain, are relatively constant in regard to their impedance as 45 seen from the output line and which are also free of changes of phase. For this purpose I prefer to use anode-loaded circuits as the couplers. A typical example of such an anode-loaded circuit is illustrated schematically in coupling unit 8, it being understood that the other coupling units 50 are similar in construction. In coupling unit 8, it will be seen that antenna unit 2 is connected to the grid 11 of an electron discharge device 12 whose anode 13 is connected through a suitable 55 load resistor 14 to a source of B power supply 15.

it being understood that the negative side of said source is connected to ground. The radio frequency output of the coupling unit is taken from anode 13 to a coupling condenser 16 which is, in turn, connected to one end of transmission line 6. The other end of said transmission line 6 being connected to the radio frequency output of coupling unit 9. Similarly the radio frequency output of coupling unit 7 is connected with the radio frequency output of coupling unit 10 by line 5. The cathode 17 is connected through a by-pass condenser 18 to ground (the chassis of the coupling unit). Bias for the cathode is supplied through a cathode resistor which is likewise used to control the gain. For this purpose the cathode 17 is connected by a lead 19 to the interior of the direction finding receiver 20. Similar leads 21, 22 and 23 connect the cathodes of coupling units 7, 9 and 10 respectively to the interior of the direction finding receiver.

As pointed out hereinbefore, the antenna system symmetry is obtained by balancing the gain from the coupling units 7-10, which in turn, is controlled by controlling the D. C. bias applied to the cathode by controlling the relative value of the cathode resistors. Furthermore, the foregoing adjustments are made so simply that an unskilled person could readily make them. For this purpose the following arrangement is employed. Leads 19 and 21 are connected to the opposite ends of the resistor of a potentiometer 24 while leads 22 and 23 are connected to the opposite ends of the resistor of a potentiometer 25. A third potentiometer 26 is employed whose movable arm is connected to ground. The potentiometers 24, 25 and 26 are interconnected by means of a multiple contact rotary switch 27 consisting of two sections 28 and 29 each having three contacts 30-32 and 33-35 respectively and having switch arms 36 and 37 respectively, said switch arms 36 and 37 being ganged together. The movable arm of potentiometer 24 is connected to contacts 30 and 32 with contact 31 being a blank. The movable arm of potentiometer 25 is connected to the switch arm 37. Contact 33 is a blank while contacts 34 and 35 are connected together and to one end of the resistor of potentiometer 26. The other end of said resistor being connected to the switch arm 36. The other connections of the direction finder may be conventional, that is, the transmission lines 5 and 6 which interconnect the antenna units, in turn, are coupled to the direction finding receiver at their midpoints over transmission lines 38 and 39. A sensing antenna 40 with a coupler 41 and a transmission line 42 is coupled into the direction finding receiver and the direction finding receiver has at its output an indicator 43, which may be in the form of a vacuum tube voltmeter arrangement such as is described in my copending application, G. S. Burroughs, for "Comparison system," Serial No. 592,401, filed May 7, 1945, now abandoned, or any other suitable indicating device.

In adjusting the antenna system in accordance with my invention, a target transmitter 44 is employed which is optically sighted so that the direction of the wave transmitted from said transmitter will be transverse and perpendicular to the common plane of the antenna units. In the first operation, the antenna system is balanced as to reception from the two upper antenna units 1 and 2. In the second step the two lower antenna units 3 and 4 are balanced. In the

third step the upper units are balanced against the lower units. In the first two steps, the balance is made as to vertically polarized waves and in the third step the balance is made as to a horizontally polarized wave, the target transmitter 44 being turned around for this last step to transmit horizontally polarized waves.

For the first step the knob of the switch 27 is turned into a first position in which switch arm 36 is on contact 30 and switch arm 37 is on contact 33. It will be seen that in this position the couplers 9 and 10 will be inoperative due to the fact that the cathode circuit is not completed to ground and so energy from antenna units 3 and 4 will not be delivered to the receiver while at the same time it will be seen that the couplers 7 and 8 associated with antenna units 1 and 2 respectively will be connected to ground through potentiometer 24 and potentiometer 26, and since, as stated before, the negative side of the "B" supply is connected to ground, a bias is provided on the cathode of coupling units 7 and 8. The relative bias on these two coupling units is then adjusted by adjusting the position of the potentiometer arm of potentiometer 24. This adjustment is made while observing the indicator 43 until a zero reading is obtained on said indicator, that is, a reading which will indicate that the input derived from antennas 1 and 2 is exactly equal.

For the second step the switch 27 is moved into the second position with arm 36 on contact 31 and arm 37 on contact 34. In this position coupling units 7 and 8 are inoperative and therefore antenna units 1 and 2 are disconnected from the receiver whereas antenna units 3 and 4 are coupled to the receiver. By adjusting the potentiometer arm of potentiometer 25 until the indicator 43 indicates a zero reading, the outputs derived from said antenna units 3 and 4 are then balanced.

The first two steps serve to balance the antenna system in regard to vertical polarization so that the antenna system is effectively symmetrical in regard to such polarization and the system is so balanced that when it is transverse and perpendicular to the direction from which energy is being transmitted, no output will be produced thus providing a sharp null.

The purpose of the third step is to eliminate the difference between the currents induced by horizontal polarization in the upper and lower portions of the antenna system and thus minimize the polarization error. For the third step the transmitter 44 is caused to transmit horizontally polarized waves. Switch 27 is then moved to its third position with switch arm 36 on contact 32 and switch 37 on contact 35. It will be seen that in this position all of the coupling units 7-10 are operative and therefore their respective antennas are coupled to the direction finding receiver. In this position the movable arm of potentiometer 26 is moved so as to produce a zero indication in the indicator 43. This balances the horizontal pick-up of the upper portion of the antenna system against the horizontal polarization pick-up of the lower portion of said antenna system. After this third step has been completed, the antenna system is substantially electrically symmetrical and is balanced in regard to horizontal polarization.

While I have described the details of one method and associated apparatus for balancing an antenna system of this type, it will be apparent to those versed in the art from my teachings

that numerous variations may be made without departing from the teachings of my invention. For example, other types of circuits, including other anode-loaded circuits than that illustrated here may be employed. Furthermore the switch 27 may be provided with other sections and other contact arms, as well as with additional potentiometers and other adjusting means, to produce various other adjusting operations in connection with the direction finding receiver. The same sequence of operations, that is, the movement of the switch 27 from one position to a next and then the adjustment of the associated control may be carried out in more complex form in regard to further adjustment of the receiver such as balancing of amplifiers therein as, for example, in my copending application C. S. Burroughs, for "Comparison system," Serial No. 592,401, filed May 7, 1945, and various other adjustments known to those versed in the art. Accordingly, while I have described above the principles of my invention in connection with specific apparatus, it is to be clearly understood that this description is made only by way of example and not as a limitation on the scope of my invention as defined in the accompanying claims.

I claim:

1. In combination, an antenna system having a plurality of upper and lower radiant acting elements mounted in the same plane, each of said elements having separate output circuits, and means controlling the gain of said upper element circuits and separate means for independently controlling the gain of said lower element circuits for balancing said outputs.

2. An arrangement as set forth in claim 1, wherein said circuits each comprise an electron discharge device having an anode load for providing constant impedance as seen from said outputs, and means controlling the relative gain of said devices balancing said outputs.

3. An antenna system comprising a plurality of upper and lower antenna units, mounted in the same plane a plurality of circuits each having its output coupled to a separate one of said units, and means controlling the relative gain of said upper unit circuits and said lower unit circuits to balance the resultant output.

4. An antenna system comprising a plurality of upper and lower antenna units mounted in the same plane and providing a radiant action pattern having a null direction, a plurality of circuits each having its input coupled to a separate one of said units, and means controlling the relative gain of said upper and lower unit circuits to produce equal outputs from said upper and lower units with respect to electromagnetic waves received from the null direction.

5. In an antenna system comprising a plurality of vertical upper and lower antenna units mounted in the same plane and interconnected by horizontal lines and providing a radiant action pattern having a null direction for vertically polarized waves, a plurality of circuits each having its input coupled to a separate one of said units and its output connected to one end of said lines, and means controlling the gain of said upper unit circuits and means separately controlling the gain of said lower unit circuits to produce equal outputs from said upper and said lower units respectively with respect to vertically polarized waves from the null direction and means for controlling the relative gain of said upper unit circuits and said lower unit circuits to produce equal outputs from said upper

and said lower unit circuits with respect to horizontally polarized waves from the null direction.

6. An "H" Adcock antenna system providing a directional pattern having a null direction, comprising a plurality of antenna units including two spaced vertical upper units and two correspondingly spaced vertical lower units with each of the lower units substantially aligned with a separate one of the upper units, a plurality of adjustable gain circuits each having its input connected to a separate one of said units, and each positioned adjacent its associated unit, a pair of substantially horizontal transmission lines interconnecting the outputs of said circuits, the output of said antenna system being taken across the midpoints of said horizontal transmission lines, means controlling the relative gain of the upper circuits to balance the outputs derived from the upper pair of units with respect to vertically polarized waves from the null direction, means controlling the relative gain of the lower circuits to balance the outputs derived from the lower pair of units with respect to vertically polarized waves from the null direction, and means controlling the gain of the upper circuits in relation to the gain of the lower circuits to balance the outputs derived from the upper pair of units with respect to that from the lower pair of units with respect to horizontally polarized waves from said null direction.

7. In a direction finding receiver, an "H" Adcock antenna system providing a directional pattern having a null direction comprising a plurality of antenna units including two spaced vertical upper units and two correspondingly spaced lower units, each of the lower units being vertically aligned with a separate one of the upper units, a plurality of adjustable gain circuits each having its input connected to a separate one of said units, a pair of horizontal transmission lines interconnecting the outputs of said circuits, a direction finding receiver, means coupling the midpoints of said lines to said receiver, means controlling the gain of the upper circuits with relation to the lower circuits to balance the outputs derived from the upper pairs of units relative to the lower pairs of units with respect to horizontally polarized waves in the null direction, means controlling the relative gain of the upper circuits to balance the outputs derived from the upper pairs of units with respect to vertically polarized waves in the null direction, and means controlling the relative gain of the lower pairs of circuits to balance the outputs derived from the lower pair of units with respect to vertically polarized waves in the null direction.

8. An antenna system according to claim 6 wherein said circuits each comprise an electron discharge device.

9. A direction finding receiver according to claim 7 wherein said variable gain circuits each comprise an electron discharge device.

10. The method of balancing an antenna system of the type providing a radiant action pattern with a directional null and having a plurality of upper and lower antenna units mounted in the same plane and each coupled to a separate adjustable gain coupler comprising arranging the antenna system in the null position with respect to a source of radiant energy and adjusting the gain of said upper unit couplers and separately adjusting the gain of said lower unit couplers until the outputs of said upper unit and said lower unit couplers are equal.

11. The method of balancing an antenna sys-

tem of the type providing a radiant action pattern with a directional null and having a plurality of vertical upper and lower antenna units mounted in the same plane and each coupled to a separate adjustable gain coupler comprising arranging the antenna system in the null position with respect to a source of radiant energy transmitting vertically polarized waves and adjusting the gain of said upper unit couplers and separately adjusting the gain of said lower unit couplers until the upper unit and the lower unit coupler outputs are equal.

12. The method of balancing an antenna system of the type providing a radiant action pattern with a directional null and having a pair of spaced vertical upper and lower antenna units mounted in the same plane and each coupled to a separate adjustable gain coupler comprising arranging the antenna system in the null position with respect to a source of radiant energy transmitting vertically polarized waves and adjusting the gain of the upper unit couplers and separately adjusting the gain of the lower unit couplers until the upper unit and the lower unit outputs derived from said couplers are equal respectively.

13. The method of balancing an antenna system of the type providing a radiant action pattern with a directional null and having a plurality of vertical upper and lower antenna units mounted in the same plane and interconnected by a pair of substantially horizontal transmission lines comprising arranging the antenna system in the null position with respect to a source of radiant energy transmitting horizontally polarized waves and adjusting the relative gain of said upper unit couplers and said lower unit couplers

until the outputs of said upper unit and said lower unit couplers are equal.

14. The method of balancing an "H" Adcock antenna system providing a directional pattern having a null direction and including two spaced vertical upper units and two correspondingly spaced vertical lower units, a plurality of variable gain couplers each having its input connected to a separate one of said units and positioned adjacent its associated unit and a pair of substantially horizontal transmission lines interconnecting the outputs of said circuits comprising arranging the antenna system in the null position with respect to a source of radiant energy transmitting vertically polarized waves, adjusting the gain of the upper couplers until the output derived from the upper antenna units is equal, adjusting the relative gain of the lower couplers until the outputs derived from the lower antenna units are equal, causing the target transmitter to transmit horizontally polarized waves and in the same null position varying the gain of the upper couplers with relation to the gain of the lower couplers until the outputs are equal.
